LINGERIE BUCKLE

Joseph Shaulson, Providence, R. I.

Application March 11, 1938, Serial No. 195,283

5 Claims. (Cl. 24—198)

My present invention relates to wearing apparel and has particular reference to a novel lingerie buckle designed for economical locking attachment.

5 It is the principal object of my invention to provide a novel buckle construction particularly designed for women's apparel, and suitable for either hand or machine locking, so as to be quickly locked in place for permitting sliding adjustment on shoulder bands, tapes and the like.

10 Another object of my invention is to provide a buckle construction which may be readily attached to tapes or the like without threading the tape through the buckle eyelets.

15 A further object of my invention is to provide a simplified buckle construction which eliminates the need for sewing or otherwise securing the end of a tape thereto.

20 With the above and other objects and advantages in view, my invention consists of a novel arrangement of parts as more fully disclosed in the detailed description following, in conjunction with the accompanying drawing, and more specifically defined in the claims appended thereto.

25 In the drawing,

Figure 1 is a perspective view showing the relative positioning of the tape or the like and the improved buckle prior to assembling;

30 Fig. 2 is a view similar to Fig. 1, the buckle being completely assembled;

Fig. 3 is a detailed view showing a modified locking arrangement;

Fig. 4 is a view of the buckle similar to Fig. 2, the tape being removed to show the interlocking engagement of the central bar portions;

35 Fig. 5 is a perspective view of a modified construction of buckle; and

Fig. 6 is a detailed view showing another modified locking arrangement.

40 It has been found desirable to provide a buckle construction for lingerie straps and tapes which does not require sewing of the tape and to the central buckle bar, and does not require threading

45 of the tape through the buckle eyes. I have therefore devised a buckle construction which may be assembled by hand or machine, the buckle parts being so designed that the assembling operation locks the free end of the tape to the buckle

50 central bar, and simultaneously threads the tape itself through the buckle eyes.

Referring to the drawing, the novel buckle 10 is of standard form, having sides 11 and ends 12, forming a buckle frame, the central bar being formed in two portions 13 and 14, as indicated

in Fig. 4, these portions interlocking when shifted from an upstanding position such as indicated in Fig. 1 to a position in the plane of the buckle as indicated in Figs. 2 and 4, to interlock. Preferably, the bar portion 13 has its end formed with a V-shaped point 15 and the bar portion 14 has its end formed with a complementary V-shaped recess 16 which is similar in shape to and cooperates with the conical point 15 to form a substantially continuous central buckle bar. 10

With the buckle in initial open position, as shown in Fig. 1, the lingerie strap or tape is folded as indicated and placed on the buckle ends 12 between the upstanding central bar portions 13 and 14, the upstanding bar portions then being forced down into the plane of the buckle, as indicated in Fig. 2, this forcing down, which may be either manually or automatically by machine catching the free end 17 of the tape, as indicated at 18, so as to lock the free end of the tape to the central bar of the buckle, the remaining portion 19 of the tape then being automatically threaded through the buckle eyes 20 and 21 formed by the interlocking engagement of the central bar portions. If more secure locking is desired particularly with larger sizes of lingerie straps or tapes, the free end 17 may be forced over one or both of the upstanding central bar portions prior to assembling, as indicated in Figs. 3, and 6, whereby a positive locking of the free end 17 to 30 the central bar of the buckle results.

Instead of utilizing interengaging conical and conically recessed ends for the central bar portions, the buckle may be formed as illustrated in Fig. 5, the upstanding portion 22 having a lateral recess 23 and the upstanding portion 24 having a corresponding lateral projection 25, whereby the forcing of the upstanding portions downwardly in the plane of the buckle 10a will interlock the projection 25 in the recess 23, and grip the free end of the tape therebetween. Other equivalent arrangements of the buckle parts may be designed, the essential feature of the invention residing in the formation of the central bar portion in sections so as to lock the free end of the lingerie strap or tape thereto during the setting of the portions together to form the central buckle bar, this formation of the central bar simultaneously and automatically resulting in the threaded positioning of the lingerie strap or tape 50 through the formed buckle eyes. Preferably, the buckles are stamped out of sheet metal, such as brass, but any metal or nonmetallic material may be used, having the necessary physical properties for retaining the final buckle formation after 55

interlocking engagement of the two central bar portions. If desired, the two central bar portions need not interlock, as each portion may be provided with means for locking engagement to the 5 tape end, such as for example prongs or the like which may be clamped to the free tape end, these clamped portions then being positioned to cooperate together as a central bar for the buckle.

While I have described specific constructional 10 embodiments of my invention it is obvious that changes in the shape of the buckle, in the relative sizes of the parts, in the materials used for the buckle, and in the means for forming of central buckle bar and for locking the central buckle 15 bar to the free tape end, may be made to suit the requirements for different buckle designs without departing from the spirit and scope of the invention as defined in the appended claims.

I claim:—

20 1. A combination buckle and tape construction comprising a frame having sides and edges and an open center, bar portions extending from opposite sides towards each other and forming a central combination buckle and tape bar element, 25 said bar portions having interlocking sections and a tape gripped between the interlocking sections, whereby said tape is locked to said buckle.

20 2. A buckle construction comprising a frame having sides and edges and an open center, bar 30 portions extending from opposite sides towards each other and forming a central buckle bar element, said bar portions having interlocking sec-

tions respectively comprising a V-shaped end and a V-shaped recess corresponding thereto and a tape gripped between the interlocking sections, whereby said tape is locked to said buckle.

3. A buckle construction comprising a frame 5 having sides and edges and an open center, and bar portions extending from opposite sides towards each other and forming a central buckle bar element, said bar portions having interlocking sections 10 respectively comprising a lateral recess and a lateral projection adapted to fit into said lateral recess when said bar portions are in the plane of the buckle.

4. A buckle construction comprising a frame 15 having sides and edges and an open center, and bar portions extending from opposite sides towards each other and interlocking to form a central buckle bar element, at least one of said bar 20 portions having a tape engaging prong whereby a tape may be pierced by said prong and gripped between said bar portions to be locked to said buckle.

5. A buckle construction comprising a frame 25 having sides and edges and an open center, and bar portions extending from opposite sides towards each other with their side edges in alignment to form a central buckle bar element, said 30 bar portions having interlocking sections respectively comprising a recess and a projection adapted to fit into said recess when said bar portions are in the plane of the buckle.

JOSEPH SHAULSON.
